CASING FOR A WEATHER INSTRUMENT OR SIMILAR ARTICLE

Donald B. Lowe, Villa Park, Ill., assignor to Airguide
Instrument Company, Chicago, Ill., a corporation of
Illinois

Filed Dec. 14, 1959, Ser. No. 58,652

Term of patent 14 years

(Cl. D52—7)

FIG. 1 is a front elevational view of a casing for a weather instrument or similar article, showing my new design;

FIG. 2 is a right-hand side elevational view thereof;

FIG. 3 is a rear elevational view;

FIG. 4 is a bottom plan view thereof;

FIG. 5 is a fragmentary detail view on an enlarged scale of the face surface of the instrument; and

FIG. 6 is a section taken along the line 6—6 in FIG. 5.

The dominant features of the design are shown in full lines.

I claim:

The ornamental design for a casing for a weather instrument or similar article, as shown and described.
